UNITED STATES PATENT OFFICE.

ISIDORO BETTINARDI AND ADOLFO TALPO, OF CHICAGO, ILLINOIS.

AUTOMATIC ELECTRICALLY-OPERATED RAILWAY-GATE.

1,269,043.

Specification of Letters Patent. Patented June 11, 1918.

Application filed January 10, 1916. Serial No. 71,331.

To all whom it may concern:

Be it known that we, ISIDORO BETTINARDI and ADOLFO TALPO, subjects of the King of Italy, and residents of Chicago, in the 5 county of Cook and State of Illinois, have invented certain new and useful Improvements in Automatic Electrically-Operated Railway-Gates, of which the following is a specification.

10 This invention relates to that class of electrically operated safety gate mechanisms for railway crossings adapted for operation by a train of cars approaching and passing the crossing, and has for its various objects:—
15 To provide automatic means in connection with the operating mechanisms of the safety gates of the system, whereby the automatic opening of said gates with the passage of one railway train is prevented by the approach of another railway train closely following said first mentioned train. The gates open automatically on the passage of said last mentioned train.

20 To provide in connection with the automatic control means of the system, a manually actuated means adapting the system for manual actuation by a station master or other authorized party at the crossing to open or close the gates independent of the 25 automatic means aforesaid.

25 To provide a structural formation and association of parts in the series of mechanisms embraced in the system, adapting the same for operation in a ready and certain manner. All as will hereinafter more fully appear.

30 In the accompanying drawings:—

35 Figure 1, is a plan view illustrating the general arrangement of the present invention in connection with a single railway track and a roadway crossing.

40 Fig. 2, is a detail plan view, partly diagrammatic, of the circuit closing mechanism of the audible or bell signal of the roadway crossing, and marked 7 on Fig. 1.

45 Fig. 3, is a similar view of one of the circuit closing mechanisms for effecting an operation of the crossing gates of the system to a closed position, and marked 11' on 50 Fig. 1.

55 Fig. 4, is a similar view of one of the series of circuit opening mechanisms, by which an interruption is effected in the circuit controlling the operation of the crossing gates to an open position, and marked 15, on Fig. 1.

60 Fig. 5, is a similar view of an auxiliary circuit closing mechanism, similar and supplementary to the mechanism illustrated in Fig. 3, and marked 11 on Fig. 1.

65 Fig. 6, is a similar view of a circuit closing mechanism for effecting an operation of the crossing gates of the system to an open position and marked 21' on Fig. 1.

70 Fig. 7, is a similar view of an auxiliary circuit opening mechanism similar to and arranged in series with the circuit opening mechanism shown in Fig. 4, and marked 17 on Fig. 1.

75 Fig. 8, is a similar view of an auxiliary circuit closing mechanism similar to and arranged in parallel circuit with circuit closing mechanism illustrated in Fig. 6, and marked 21 on Fig. 1.

80 Fig. 9, is a similar view of another auxiliary circuit opening mechanism, constituting the primary element of the series of opening mechanisms illustrated in Figs. 4, 7 and 10, and marked 18 on Fig. 1.

85 Fig. 10, is a similar view of another auxiliary circuit opening mechanism, constituting the terminal element of the series of opening mechanisms illustrated in Figs. 4, 7 and 9, and marked 18' on Fig. 1.

90 Fig. 11, is a similar view of the connections to a companion track system and to the battery of the system.

95 Fig. 12, is a similar view of the transverse branch connections between the pairs of bell and gate operating mechanisms at the roadway crossing.

Fig. 13, is a detail sectional plan view of one of the plurality of circuit closing mechanisms of the system.

Fig. 14, is a longitudinal sectional elevation of the same.

Fig. 15, is a transverse section on line $x-x$, Fig. 13.

Fig. 16, is a transverse section on line $x'-x'$, Fig. 13.

Fig. 17, is a detail longitudinal section on line x^2-x^2 Fig. 13.

Fig. 18, is a detail elevation of the under side of the cover plate of the housing of the circuit closing mechanism.

Fig. 19, is a detail transverse section on line x^3-x^3 , Fig. 18.

Fig. 20, is a transverse section on line x^4-x^4 , Fig. 13.

Fig. 21, is an enlarged top view of the resilient contract finger or bar and the associated resilient prong by which it is actuated in one direction.

Fig. 22, is a detail sectional plan view of one of the plurality of circuit breaking or interrupter mechanisms of the system.

Fig. 23, is a longitudinal sectional elevation of the same.

Fig. 24, is a transverse section on line x^5-x^5 , Fig. 22.

Fig. 25, is a transverse section on line x^6-x^6 , Fig. 22.

Fig. 26, is a transverse section on line x^7-x^7 , Fig. 22.

Fig. 27, is a detail elevation of the operating bar of the circuit opening mechanism.

Fig. 28, is a horizontal section on line x^8-x^8 , Fig. 31, illustrating the motor mechanism in the base of the housing of a crossing gate of the system.

Fig. 29, is a similar view on line x^9-x^9 , Fig. 31, illustrating the intermediate operative connections of the same.

Fig. 30, is a similar view on line $x^{10}-x^{10}$, Fig. 31, illustrating the pole changing mechanism and accessories.

Fig. 31, is a detail longitudinal sectional elevation of a crossing gate mechanism.

Fig. 32, is a transverse sectional elevation of the same.

Fig. 33, is a detail elevation of the stationary member or element of the pole changer of the gate mechanism.

Fig. 34, is a section of the same on line $x^{11}-x^{11}$, Fig. 33.

Fig. 35, is a similar view on line $x^{12}-x^{12}$, Fig. 33.

Fig. 36, is a detail elevation of the semi-rotary member or element of the pole changer above referred to.

Fig. 37, is a section of the same on line x^{13} , Fig. 36.

Fig. 38, is a similar view on line $x^{14}-x^{14}$, Fig. 36.

Fig. 39, is an enlarged sectional elevation of the switch mechanism associated with the aforesaid pole changer, and adapted to automatically control an electric signal lamp carried on a movable arm of a crossing gate.

Fig. 40, is a transverse section of the same, on line $x^{15}-x^{15}$, Fig. 39.

Fig. 41, is a horizontal section of the same, on line $x^{16}-x^{16}$, Fig. 39.

Fig. 42, is an elevation of one of the crossing gates in a down or closed position.

Fig. 43, is a similar view of the same in an up or open position.

Fig. 44, is a detail plan of the crossing gate, with parts in section.

Fig. 45, is a detail transverse section of the main gate arm on line $x^{17}-x^{17}$, Figs. 42 and 44.

Fig. 46, is a similar view on line $x^{18}-x^{18}$, Fig. 42, of the upper part of the gate arm.

Fig. 47, is a similar view of the lower part of said gate arm.

Fig. 48, is a detail sectional elevation of the switch mechanism, adapted for manual actuation at a station adjacent to the roadway crossing to open and close the crossing gates independent of the automatic track mechanism control, said switch mechanism being shown in its normal open condition.

Fig. 49, is a horizontal section of the same, on line $x^{20}-x^{20}$, Fig. 48.

Fig. 50, is a detail elevation, similar to Fig. 48, and showing the parts in a closed condition.

Fig. 51, is a sectional elevation of the station at the roadway crossing, in which are located the manually actuating mechanisms of the system.

Fig. 52, is a front elevation of the casing for the manual switch mechanism aforesaid, and illustrating the operating means thereof.

Fig. 53, is a diagrammatic view, illustrating the arrangement of the various circuits of the system.

Similar reference numerals indicate like parts in the several views.

The present signaling and safety gate system is adapted for installation upon a single track, see Fig. 1, or a pair of parallel tracks, see Fig. 53, crossing an ordinary roadway, or if desired may be installed on any number of tracks crossing said roadway or one or more intersecting tracks of another railway. The duplication of tracks in the last mentioned instances requiring a duplication of the electrical actuating mechanisms of the first mentioned tracks and an interconnection of portions of said mechanisms to coact in keeping the crossing gates closed during periods of danger.

Accordingly the present system as applied to a double track railway and as illustrated in Fig. 54 will comprise detail formation and association of parts as follows:

3 designate safety gates, hereinafter described in detail, arranged at the respective sides of the tracks 1 and 2, and adapted to present a barrier at the roadway aforesaid during a period of danger due to the passage of a railway train.

4 designates an electric battery or other usual source of electro-motive force, arranged adjacent to the roadway crossing and having supply and return conductors 5 and 6, connecting said battery 4 with series of

circuits of the present system hereinafter described. As usual in the present class of signaling systems, the supply or main line 5 will branch to different parts of the system to supply electro-motive force to the different independent circuits of the system.

7 designate a series of four circuit closers, each one of which is arranged adjacent to an individual track rail of the tracks 1 and 2, and adapted to be moved to a closed position by the wheels of a train of cars passing along the track toward the crossing to be guarded. Each of said circuit closers is disposed a proper distance away from the crossing, say one mile and has one of its insulated terminal or contact points in electrical connection with the main supply line 5 aforesaid, while its companion terminal or contact point is in electrical connection 15 with a line wire or conductor, 8, extending to an automatic switch 9 in the housing of the gate 3, and from said switch to a signal bell 10 disposed in an elevated position above the aforesaid gate housing, and 20 adapted to give an audible signal while the aforesaid circuit closer 7 remains in its closed condition as hereinafter more fully described.

11 designate a series of four circuit closers, each one of which is arranged adjacent to an individual track rail of the tracks 1 and 2, and adapted to be moved to a closed position by the wheels of a train of cars passing along the track toward the crossing to be guarded. Each of said circuit closers is located a distance much nearer the crossing than the heretofore described circuit closer 7 of the bell 10, and so that said bell may have an extended period of action 35 and give warning of an approaching train before the closing of the gate or gates 3, and to such end the distance of each circuit closer 11 from the crossing may be two hundred yards, more or less. One of the insulated terminal or contact points of each circuit closer 11 is in electrical connection with the main supply line 5 aforesaid, while the companion terminal or contact point is in electrical connection with a line or conductor 40 12 which extends to an automatic pole changer 13 in the housing of the safety gate 3, and from said pole changer 13 to an electric-motor mechanism 14 by which the arms of the gate are moved to a down or 45 closed position, as hereinafter described in detail.

In the present system, the pole changer 13 aforesaid, is operatively connected with the gate closing and opening mechanisms in 50 manner hereinafter described in detail, and is adapted to effect a reversal of the direction of the electric current to the electric motor 14, and so that as the gate arm reaches its final down or closed position, the pole

changer 13 will have automatically shifted, 65 to change the direction of the electric current to motor 14, and the same will be in condition to effect a movement of said gate arm to an up or opened position, and vice versa.

70 11' designate a secondary series of circuit closers, the counterpart of the circuit closers 11 just described, both as to arrangement and actuation, and connected in parallel therewith with the line wires 5 and 12 75 as shown in Fig. 53. Each of said circuit closers 11' is located nearer the crossing than its companion circuit closer 11 aforesaid, and is adapted to act auxiliary thereto in effecting a full closure of the crossing 80 gates in cases where the same may be in a partly closed condition, which may occur where trains run often, as well as back and forth, in the zone of the present system. Where conditions require further duplication, 85 other auxiliary circuit closers, similar to the aforesaid circuit closers 11 and 11' may be inserted in parallel with the others in the aforesaid, lines 5 and 12.

15, 16 and 17 designate one group of a 90 series of four groups of normally closed circuit interrupters or breakers associated with the railway tracks 1 and 2 and located on either side of the roadway crossing and intermediate the same and the primary series of circuit closers 11 above described. Each circuit interrupter, 15, 16 and 17 of the aforesaid group is arranged adjacent to an individual track rail of the railway track 1, and to the left of the roadway crossing 95 100 as shown in Fig. 53, and said group of interrupters are adapted to be serially moved into an open position by the wheels of a train of cars passing to the right on track 1 toward the roadway crossing to be 105 guarded.

15¹, 16¹, 17¹, and 18¹, designate another group of the series of four groups of normally closed circuit interrupters aforesaid. Each circuit interrupter of the group is arranged adjacent to an individual track rail of the railway track 2, and to the left of the roadway crossing as shown in Fig. 53, and are adapted to be moved into an open 110 115 position by the wheels of a train of cars passing to the right on the track 2 toward the roadway crossing aforesaid.

15², 16², 17², 18² designate another group of the series of four groups of circuit interrupters aforesaid. Each circuit interrupter 120 of the group is arranged adjacent to an individual track rail of the track 2, and to the right of the roadway crossing as shown in Fig. 53, and is adapted to be moved into an open position by the wheels of a train of 125 cars passing to the left on track 2 toward the roadway crossing aforesaid.

15³, 16³ and 17³, designate another group

of the series of four groups of circuit interrupters aforesaid. Each circuit interrupter of the group is arranged adjacent to an individual track rail of the railway track 1, 5 and to the right of the roadway crossing, as shown in Fig. 53, and is adapted to be moved into an open position by the wheels of a train of cars passing to the left on track 1 toward the roadway crossing aforesaid.

As illustrated in diagram view Fig. 53, the circuit interrupters of the four groups above described are connected in series by a line wire or conductor 19, and at the respective ends, the connected groups are electrically connected with circuit interrupters now to be described.

18 designates a normally closed circuit interrupter, similar to the circuit interrupters above described, and located between the circuit interrupter 17 of the first group aforesaid and the roadway crossing. The interrupter 18 is arranged adjacent to an individual track rail of the railway track 1 and to the left of the roadway crossing and is adapted to be moved into an open position by the wheels of a train of cars passing to the left on the track 1 and in a direction away from the roadway crossing. 20 One terminal point of said interrupter has electrical connection with the main line 5, while the other terminal of said interrupter has electrical connection by line wire 19 aforesaid with the next adjacent circuit interrupter 17 of the series of four groups of interrupters above described.

18³ designates a normally closed circuit interrupter, similar to the circuit interrupters above described, and located between the circuit interrupter 17³ of the last group aforesaid, and the roadway crossing. The interrupter 18³ is arranged adjacent to an individual track rail of the railway track 1 and to the right of the roadway crossing, 45 and is adapted to be moved into an open position by the wheels of a train of cars passing to the left on the track 1 and in a direction toward the roadway crossing. One terminal of said interrupter 18³ is electrically connected in series with the adjacent interrupter 17³ of the last group aforesaid. The other terminal of the interrupter 18³ is connected in series, by line wire 20, with the groups of circuit closers now to be described:—

21, 22, 23, and 24 designate a series of four circuit closers arranged adjacent to individual track rails of the tracks 1 and 2, and adapted to be moved into a closed position by the wheels of a train of cars passing along the tracks toward the roadway crossing aforesaid.

21¹, 22¹, 23¹, and 24¹ designate a companion series of four circuit closers arranged 65 adjacent to individual track rails of the

tracks 1 and 2 and adapted to be moved into a closed position by the wheels of a train of cars passing along the tracks away from the roadway crossing aforesaid.

As illustrated in Fig. 53, a pair of the aforesaid circuit closers are associated with each group of the four groups of circuit interrupters above described, and alternately therewith preferably in the manner shown. Each pair, 21, 21¹; 22, 22¹; 23, 23¹ and 24, 24¹ of said series of circuit closers are arranged in parallel between the line wires or conductors 20 and line wires or conductors 25, extending to the terminal or contact point 101, of the pole changer of the gate mechanism, to effect an operation of the same to raise or open the crossing gates,

It is within the scope of this part of the present invention to increase or diminish the number of circuit closers and circuit interrupters heretofore described, in accordance with the extent of automatic protection required at the particular place to be guarded, and also in accordance with the number of tracks at a particular crossing, and the extent of movement of trains back and forth past the crossing. In this connection an arrangement adapted for a single railway track is shown in Fig. 1 of the drawings.

26 designates a circuit closer, hereinafter described in detail, arranged within a station house or other inclosure adjacent to the roadway crossing. Said circuit closer is adapted for manual actuation and is arranged in an individual circuit which embraces the main line wire 5 aforesaid, and a line wire or conductor 27, shown in Fig. 53. The circuit closer 26 has line connections with the terminals of the pole changer of the gate operating mechanism, herein-after described. Such provision enables the station master or other attendant at the roadway crossing, to effect an opening or a closing of the gates independent of the automatic mechanism, heretofore referred to.

28 designates a signal lamp disposed adjacent to the outer zone of the gate closing portion of the system, and adapted to enable a station master or other attendant adjacent to the roadway crossing to signal the engineer of an approaching train. To such end said signal lamp will be arranged in an individual circuit extending from the crossing to said lamp, with its controlling switch 29 arranged in the station house or inclosure above mentioned.

The series of circuit closers and circuit interrupters associated with the railway tracks in the present system, are preferably housed and supported by the following means:—

30 designates an elongated housing secured in adjacent and spaced relation to one of the track rails, and such housing may be individual to a remote circuit closer, such

as the circuit closers 7, aforesaid, or said housing may be of an extended formation and adapted to contain a series of circuit closers and an alternating series of circuit interrupters hereinafter described. In the construction in Figs. 13 to 26, inclusive, the housing 30, will comprise one or more elongated plates 31, having a bottom flange 32 by which they are secured to the track ties, to constitute the outer vertical wall of the housing 30.

33 designates a coupling plate for connecting adjacent ends of the wall plates 31 together in an extended structure. The coupling plate 33, is adapted in addition, to afford a substantial support for one of the hereinafter described operating springs of an individual circuit mechanism.

34 designate one or more elongated plates, similar to the plates 31 and having spaced relation thereto, to constitute the inner vertical wall of the housing 30. Said inner wall is formed with one or more openings for the movement of one or more of the hereinafter described laterally shifting operating bars of the circuit closers, or like bars of the circuit interrupters, heretofore referred to.

35 designates the bottom plate of the housing 30, preferably formed with a series of drainage openings 36, for the outflow of any water collecting in the housing.

37 designates the top or cover plate for the housing 30, formed in sections where an extended housing is to be covered, and provided on its under surface with depending lugs 38, adapted to position the cover on the side walls of the housing 30, and to receive transverse attaching screws by which the cover is secured in place in a removable manner, as shown in Fig. 17, so that access may be had to the contained parts for inspection and repair.

39 designate supports for the line wires or conductors of the system and fixed on the interior face of the wall 31, and near the top of the same as shown in Figs. 22, 23 and 24.

The series of circuit closers disposed along the railway tracks are of a counterpart construction, and each circuit closer will have a detail construction as follows:—

40 designates an operating bar arranged in an opening in the inner wall 34 of the housing 30 and adapted to have movement through said opening. Said operating bar 40, is of a U shape in cross-section for the purpose hereinafter stated, and is held from longitudinal movement with relation to the housing 30 and adjacent track rail, by guide pins or lugs 41 on its under side and having movement in transverse guide slots 42 in guide plates 43 secured in the bottom position of the housing 30, as shown in Fig. 13.

45 With the described connection a free lateral

floating movement of the operating bar 40, can take place, and only limited in extent by the length of the aforesaid guide slots 42.

44 designates a spring secured at one end to the inner wall 34 of the housing 30, by bolts 45 or like fastening means. The free end of said spring is provided with a guide pin or stud 46 stud 46 adapted for guiding engagement in an elongated guide slot 47 at one end of the operating bar 40 aforesaid, and adapted to yieldingly hold said end of the operating bar 40 away from the adjacent track rail as illustrated in Figs. 13 and 14.

48 designates a spring similar to the spring 44 above described, and secured at one end to the outer wall 31 of the housing 30 by bolts 49, or like fastening means. The free end of said spring 48 is provided with a guide pin or stud 50 adapted for guiding engagement in an elongated guide slot 51 at the other end of the operating bar 40 aforesaid, and adapted to yieldingly hold said end of the operating bar in close relation to the adjacent track rail, as shown in Figs. 13 and 14.

With the above described formation and association of parts, the flanges of the wheels of a train of cars moving to the right in Fig. 13 will act against the inner face of said operating bar to move the end of the same controlled by spring 48 away from the track rail and establish electrical connection between the contact points hereinafter described in detail.

With a train of cars moving in a direction to the left in Fig. 13, the flanges of the car wheel will ride in the channel provided by the U shape of said operating bar 40, and move said bar into close parallel relation to the adjacent track rail against the resilient stress of the spring 44. In such last mentioned operation, the circuit embracing the contact points of the device are not brought into electrical connection and said circuit remains broken.

The advantage resulting from the above described construction is that by a simple end to end reversal of the circuit closer, the same can be used for closing a circuit when a train is passing in one direction or the other, and with a corresponding inaction of the circuit closer when the train is moving in a reverse direction to that for which the circuit closer is placed.

52 and 53 designate a pair of contact points or terminals secured in an insulated manner on the vertical wall 31 of the housing 30 aforesaid, and forming a break in the line wire or conductor with which the circuit closer is associated.

54 designates a resilient contact member secured to the outer wall of the housing 30 aforesaid, and having electrical connection with the contact or terminal 52 aforesaid, and adapted when flexed to contact with the

other terminal 53, to establish communication along the line wire or conductor aforesaid.

55 designates a resilient bearing finger secured at one end to the operating bar 40 aforesaid, and adapted for bearing against the resilient contact member 54 to yieldingly transmit thereto the movement of said operating bar 40 in one direction. The movement of said parts in the other direction is attained by the resiliency of the contact member 54 and bearing finger 55.

56 designates an electro-magnet associated with a free portion of the contact member 54, which is adapted to constitute an armature for said electro-magnet. The windings of said electro-magnet are in circuit with the line wire of the circuit closer, and the arrangement is such, that as the resilient contact member 54 is moved outward to close the circuit between the terminals 52, 53, said contact member 54 will be held by the magnetic attraction of the electro-magnet in such closed condition, regardless of the return of the operating bar 40 to its normal position and until the circuit is broken by the pole changer 13 of the system. In the described circuit closing mechanism, the normal condition of parts is in open circuit.

The series of interrupters disposed along the railway tracks are of a counterpart construction, and each circuit interrupter will have a detail construction as follows:

57 designates an operating bar associated with an opening in the inner wall 34 of the housing 30 and adapted to have movement through the same. Said operating bar 57 is of a U shape in cross-section for the purpose hereinafter stated, and is held from longitudinal movement with relation to the housing 30 and adjacent track rail, by guide pins or lugs 58 on its under side and having movement in transverse guide slots 59 in guide plates 60 secured in the bottom portion of the housing 30, as shown in Figs. 22 to 27, inclusive. With the described connection a free lateral floating movement of the operating bar 57 can take place, and only limited in extent by the length of the aforesaid guide slots 59.

61 designates a spring secured at one end to the inner wall 34 of the housing 30 by bolts 62 or like fastening means. The free end of said spring is provided with a guide pin or stud 63 adapted for guiding engagement in an elongated guide slot 64 at one end of the operating bar 57 aforesaid, and adapted to yieldingly hold said end of the operating bar 57 away from the adjacent track rail, as illustrated in Figs. 22 and 23.

65 designates a spring similar to the spring 61 above described, and secured at one end to the outer wall 31 of the housing 30 by

bolts 66 or like fastening means. The free end of said spring 65 is provided with a guide pin or stud 67 adapted for guiding engagement in an elongated guide slot 68 at the other end of the operating bar 57 aforesaid, and adapted to yieldingly hold said end of the operating bar in close relation to the adjacent track rail, as shown in Fig. 22.

The function and operation of the operating bar 54 and its described accessories, is similar to the operating bar 40 and its accessories of the circuit closer, heretofore described in detail.

69 designates a contact point or terminal secured in an insulated manner on the outer vertical wall of the housing 30, and constituting one end of a break in the line wire or conductor with which the circuit interrupter is associated.

70 designates a resilient contact member secured in an insulated manner on the operating bar 57 aforesaid, and adapted for normal resilient contact with the terminal 69 above described. Said contact member is in electrical connection with the other end of the aforesaid break in the line wire or conductor, so that the normal condition of the parts is in closed circuit.

With the above described construction the flanges of the wheels of a railway train moving to the left in Fig. 22, will ride in the channel provided by the U shape of said operating bar 57 and move said bar into close parallel relation to the adjacent track rail against the resilient stress of the spring 61, and cause an interruption in the line wire or conductor aforesaid.

With a railway train moving in a direction to the right in Fig. 22, the wheel flanges will act against the inner face of said operating bar to move the end of the same controlled by the spring 65 outwardly, and no interruption in the circuit will take place.

The plurality of crossing gates 3 of the system, will each comprise a closed box or housing of any usual and suitable form, preferably provided with hinged end walls 71, to afford convenient access to the enclosed mechanisms of the gate.

72 designates the bottom or base member of the housing provided with a duct or passage for the line wires or conductors 6, 8, 9, 12, and 25, heretofore described, and by which the mechanism within the gate housing is controlled.

73 designates an electric motor of the direct current type and of any usual form, see Figs. 28, 31 and 32, secured to the bottom 72 of the gate housing and provided with a driving pinion 74 on its armature shaft.

75 designates an intermediate shaft journaled in the side walls of the gate housing and provided with a gear wheel 76 having

operative engagement with the pinion 74 aforesaid. Said shaft 75 also carries a pinion 77.

78 designates a countershaft also journaled in the side walls of the gate housing and provided with a gear wheel 79 having operative engagement with the pinion 77 aforesaid. Said countershaft 78 also carries a crank arm 80, adapted for operative connection with the movable portions of the gate now to be described.

81 and 82 designate a pair of rock shafts journaled in horizontally spaced relation in the side walls of the gate housing, and having crank arms 83, 84, operatively connected by links 85 and 86 with the aforesaid crank arm 80 of the countershaft 78, above described. Said rock shafts 81, 82, extend out through the side walls of the gate housing and carry the main and auxiliary gate arms, hereinafter described in detail.

In the preferred construction shown, the connection between the rock arm 84 and its link 85 and the rock arm 80 is by means of a pin and elongated slot formation 85' as shown in Fig. 31. Said construction is adapted to permit an opening of auxiliary gate arm 128, hereinafter described, when said gate arm is in a closed condition, and 30 the liability to damage of the automatic mechanism of the gate is prevented, which would otherwise occur if an impatient pedestrian attempts to raise the auxiliary gate and pass by.

87 designates a lateral pin or tappet carried by the crank arm 84 aforesaid, and is adapted for intermittent operative engagement with the movable element of the pole changer 13 hereinafter described.

88 designates a movable contact arm carried by the rock shaft 81 and forming the movable member of an electric switch by which an electric signal lamp on the main gate arm is controlled, as hereinafter set forth.

89 designates a pair of insulated contact points carried by the movable arm 88 aforesaid, and forming the terminals of one of the line wires or conductors 90 which include 50 the signal lamp 91, of the main gate arm in circuit.

92 designates the fixed member of the switch just referred to, provided with a pair of insulated segmental contact plates 93 arranged in spaced relation and is adapted for individual contact with the contacts 89 aforesaid, in one position of the arm 88 carrying the same. The contact plates 93, are connected with the main supply and return wires 5 and 6 of the system in any usual manner. In actual use, the pairs of contact members 89 and 93 are out of electric connection when the gate arms are in the raised and open position, and are automatically

brought into contact, to supply current to 65 the signal lamp 91 of the gate arm as the same moves into a lowered or closed position.

94 designates an upright tubular post attached to the top of the gate housing and 70 carrying at its upper end the signal bell 10 heretofore referred to. Said tubular post carries the line wires 95 embracing said bell and connected to switch 9, heretofore referred to, and to the return line 6 of the 75 system.

The switch or circuit interrupter 9 aforesaid, preferably comprises a pair of spaced and insulated terminals 96 connected respectively with the line wires 8 and 95 aforesaid, and a pivoted contact arm 97, bridging said terminals to normally maintain the line in closed circuit. In the practical operation of this part of the system, the contact arm 97 is intermittently and momentarily 85 actuated to break the circuit, as a preliminary to an ultimate break in the circuit at the track circuit closer 7 heretofore described. The actuation of the contact arm 97 is automatically effected by a trip dog 98 carried 90 by the semi-rotary member of the pole changer 13, hereinafter described.

99 designates the supporting base of the fixed member of the pole changer 13, heretofore referred to, and preferably of the circular form shown. Said base carries the above mentioned terminal points of the line wires 8 and 95 and the contact arm 97 associated therewith, and in addition the following terminal or contact points:—

100 and 101 designate a pair of outer terminals or contact points arranged in circularly spaced relation on the base 99 and having individual connection with and forming the respective terminals for the line wire 12 105 and 25, of the track circuit closers heretofore described.

102, 103 and 104 designate an inner series of three terminal or contact points arranged in concentric relation to the aforesaid outer 110 contact points 100, 101, and in circularly spaced relation on the base 99. The middle terminal 102 has line wire connection 105, with the field of the motor 14, while the companion terminals have wire connections 115 106 and 107 with the armature brushes of said motor 14, in manner usual to reversible electric motors.

108 designates a bearing shaft or arbor having fixed central relation in the insulating base 99 aforesaid, and is adapted to pivotally support the movable or semi-rotary member of the pole changer now to be described.

109 designates a disk of insulating material having a central orifice for journal engagement on the arbor 108 aforesaid, and provided with a pair of prongs 110 in spaced

relation at its periphery and adapted for intermittent operative engagement with the before described pin or tappet 87 of the gate operating mechanism. With the described 5 association of parts, as the tappet 87 nears the end of its movement in one direction it will engage one of the prongs 110, and impart thereto and to the disk 109 a partial rotation in one direction. In like manner 10 as the tappet 87 nears the end of its movement in the other direction it will engage the other of said prongs 110 and impart thereto and to the disk 109 a partial rotation in the other direction. As a result of 15 the above, the pole changer receives intermittent actuation in one direction or the other to reverse the directions of the operating circuits of the electric motor 14, so that the same will run in one or the other 20 directions in accordance with the conditions prevailing in the system.

111 and 112 designate a pair of segmental contact plates secured to the insulating disk 109 aforesaid, and adapted for electrical 25 contact with the aforesaid terminals of the base 99 in manner hereinafter stated.

113 designates a radially extending contact finger forming a part of the contact plate 111 and associated with outer pair of 30 terminal contact points 100, 101, and adapted for alternate contact therewith in accordance with the position of the movable member of the pole changer 13. In the construction shown, the contact plate 112, is 35 adapted to electrically connect the terminal 102 of the line wire 105 of the motor field, one or the other of the terminals 103 or 104 of the line wires 106 and 107 to the motor brushes in accordance with the position 40 of the movable member of the pole changer. In like manner, the contact plate 111 and its contact finger 113 are adapted to electrically connect one or the other of the terminals 100 or 101 of the track lines 12 45 and 25 with one or the other of the terminals 103 or 104, in accordance with the position of the movable member of the pole changer. With the described association of parts, the circuits of the electric motor 14, 50 are automatically changed and the motor caused to run in the direction required, to either open or close the crossing gate, upon the closing of a particular track circuit closer of the system.

55 114 designates a spring surrounding the arbor 108 aforesaid, and adapted to resiliently hold the movable member of the pole changer in proper operative position.

The trip dog 98, heretofore described, is 60 pivoted on the disk 109 aforesaid, in operative relation to the pivoted contact arm 97 aforesaid, and said trip dog 98 is preferably of the gravity type shown in Fig. 36.

115 designates a resilient arm carried on the rock shaft 81 of the main gate arm 65 aforesaid, and adapted in the turning movement of said rock shaft, in one direction or the other, to come in contact with the ends of a segmental yoke 116, secured to an inner wall of the gate housing. And with a view 70 to retarding the final movement of said rock-shaft 81, and its accessories, the yoke 116 will be formed with inclined portions 117 adapted to afford bearings for the free end 75 of the resilient arm 115, to frictionally retard the final movement of the parts.

The main gate arm heretofore referred to, preferably comprises a detail construction as follows:—

118 designates a yoke or frame having 80 fixed attachment to the rock shaft 81 aforesaid, and carrying a suitable counterbalance weight 119, as shown in Figs. 42, 43 and 44.

120 designates a pair of gate rails secured to the yoke 118 aforesaid, and to intermediate reinforcing bracket 121, and arranged in spaced relation to provide an intermediate space for the reception of a series of depending links or pickets 122, which are pivoted at their upper ends between said 90 rails, and constitute a visible portion of the gate arm.

123 designate rails pivotally attached to the lower ends of the pickets 122, and constituting another visible portion of the gate 95 arm. The described pivotal connection of the parts permit the same to fold compactly together as the gate arm moves into a raised or open position.

135 designates a containing channel 100 formed in one of the gate rails 120 aforesaid, and in one of the yoke members 118 aforesaid, and adapted to contain the line wires 90 of the signal lamp 91, heretofore described and which is carried on the free 105 end of the main gate arm, said channels or passages are provided with removable covers 126, to afford convenient access to said line wires, as illustrated in Figs. 46 and 47.

127 designates a channel or passage formed in an end portion of the rock shaft 81 of the gate arm, and adapted to contain a portion of the line wires 90 aforesaid, which extend from the terminals 89 before 115 described, to the lamp 124, and as illustrated in Figs. 39, 40 and 41.

128 designates the auxiliary or short arm of the crossing gate, associated with the sidewalk of the crossing to govern the passage of pedestrians along the same. Said arm 128 is fixed to an end of the rock shaft 82 before described, and is adapted to open and close in unison with the main gate arm above described.

129 designates the house or inclosure

heretofore referred to, and arranged adjacent to the roadway crossing of the system. Said house is adapted to contain the auxiliary controlling portion of system, and which 5 is capable of manual actuation by a station master or other authorized person.

130 designates a closed casing arranged within the house 129, and provided with an insulating base plate 131, to which is attached a local switch 132, and an electromagnetic circuit closer 26, heretofore referred to, and now to be described in detail.

133, 134 and 135 designate a series of conducting plates secured to the insulating base 131, in separated relation as shown in Fig. 48. The conducting plate 133, is connected with the main supply line 5 of the system, while the conducting plate 135 is connected by a line wire or wires 137, forming branches of the line wires 12 and 25 of the terminals 100 and 101 of the pole changer 13 aforesaid.

The intermediate conducting plate 134 of the series is provided with a contact point 138, and is electrically connected with the windings of an electro-magnet 139, and through said windings with the conducting plate 133 aforesaid, by a line wire 136, as illustrated in Fig. 48.

30 140 designates a contact arm, preferably of the weighted type shown in Fig 49, and pivoted in an electrically conductive manner on the conducting plate 135, and the arrangement is such that as said arm 140 is 35 moved down by hand into contact with the terminal or contact 138 aforesaid, electric communication will be established between the plates 134 and 135, and the electro-motive force will pass to the terminals 100 or 40 101 of the pole changer, to effect either an opening or closing movement of the crossing gate as the case may be.

141 designates an armature carried by the contact arm 140, and adapted to be held in 45 contact with the core of the electro-magnet 139 while the electric current is passing therethrough.

The normal position of the contact arm 140, is in open circuit, as illustrated in Fig. 50 and it is moved into a position of closed circuit, illustrated in Fig. 50 by hand and is held therein by the electro-magnet 139 during the period in which current is passing through said electro-magnet to effect an 55 opening or a closing of the crossing gate as the case may be. With the final opening or closing of the gate the circuit is broken by the pole changer 13 in the gate housing in manner heretofore described, and 60 the contact arm 140 automatically moves back into its normal open circuit position.

142 designates a lateral operating stem on the free end of the contact arm 140, ex-

tending and through an opening in the face of the casing 130 and provided with a 65 knob or handle for convenient manual operation of the contact arm.

132 designates the local electric-switch above referred to, arranged in the casing 130, and interposed in a branch circuit 143 which extends to and is connected to the line wires 90 of the signal lamp 91 of the roadway crossing, to provide means for the manual control of the same from the roadway crossing.

The switch 29 of the track signal lamp 28 heretofore described will be arranged in the house or inclosure 129, as illustrated in Fig. 52.

Operation of the system.

The mode of operation of the signal bell at the roadway crossing; the automatic closing of the crossing gates and the subsequent opening of the same, as well as the automatic control of the signal lamp on the crossing gates is fully set forth in the detail description of parts and accordingly further description of the operation of the system will be confined to the functions of the auxiliary circuit closers and circuit interrupters disposed along the railway tracks of the system.

In the event of railway trains running in opposite direction toward the roadway crossing, or of two or more railway trains following each other closely upon the same track, or of divers railway trains moving within the zone of action of the system, the opening of the crossing gates due to the passage 95 of the first train past the normal opening point for an opening operation of the gates, is neutralized by one or more of the circuit interrupters 15, 16, 17, etc., by any succeeding train entering the zone of action in one 100 direction or the other and upon either of the railway tracks, and the crossing gates will remain in their closed condition until the last train is leaving such zone of action, and to such end the series secondary circuit 110 closers 21', 22', 23', 24', arranged in a reversed direction to and in parallel circuit with the series of primary circuit closers 21, 22, 23 and 24, are employed and as a particular secondary circuit closer is operated by a 115 railway train leaving the zone of action to establish the opening circuit of the gate mechanism to effect an opening of the crossing gates.

Having thus fully described our said invention what we claim as new and desire to secure by Letters Patent, is:—

1. In an electrically actuated gate for railway crossings, the combination of a movable gate arm, a motor operatively connected 125 thereto, a pole changer associated with said

motor, and a plurality of electro-magnetic circuit closers, operative in one direction only, disposed along the tracks in reversed relation for actuation by trains moving in opposite directions respectively and connected with opposite terminals of the pole changer, substantially as set-forth.

2. In an electrically actuated gate for railway crossings, the combination of a movable gate arm, a motor operatively connected thereto, a pole changer associated with said motor, a plurality of electro-magnetic circuit closers, operative in one direction only, disposed along the tracks for actuation by trains moving in opposite directions respectively and connected with opposite terminals of the pole changer, and a circuit interrupter, operative in one direction only, disposed along the tracks and adapted to interrupt the circuit of one of the circuit closers aforesaid, substantially as set-forth.

3. In an electrically actuated gate for railway crossings, the combination of a movable gate arm, a motor operatively connected thereto, a pole changer associated with said motor, a plurality of electro-magnetic circuit closers, operative in one direction only, disposed along the tracks and connected with opposite terminals of the pole changer, a second plurality of electro-magnetic circuit closers, operative in one direction only, disposed along the tracks for actuation by trains moving in opposite directions respectively and connected to opposite terminals of the pole changer, the two pluralities of circuit closers being arranged in reverse directions, and a series of circuit interrupters, operative in one direction only, disposed along the tracks and adapted to interrupt the circuits of the circuit closers aforesaid, substantially as set-forth.

4. In an electrically actuated gate for railway crossings, the combination of a movable gate arm, a motor operatively connected thereto, a pole changer associated with said motor, a plurality of electro-magnetic circuit closers, operative in one direction only, disposed along the tracks in reversed relation for actuation by trains moving in opposite directions respectively and connected with opposite terminals of the pole changer, an electro-magnetic switch arranged adjacent to the crossing and adapted for manual closing, an individual circuit embracing said switch and the opposite terminals of the pole changer, substantially as set-forth.

5. In an electrically actuated gate for railway crossings, the combination of a movable gate arm, a motor operatively connected thereto, a pole changer associated with said motor, a plurality of electro-magnetic circuit closers, operative in one direction only, disposed along the tracks and connected with opposite terminals of the pole changer, a circuit interrupter, operative in one direction only, disposed along the tracks and adapted to interrupt the circuit of one of the circuit closers aforesaid, substantially as set-forth.

circuit interrupter, operative in one direction only, disposed along the tracks and adapted to interrupt the circuit of one of the circuit closers aforesaid, an electro-magnetic switch arranged adjacent to the crossing and adapted for manual closing, and an individual circuit embracing said switch and the opposite terminals of the pole changer, substantially as set-forth.

6. In an electrically actuated gate for railway crossings, the combination of a movable gate arm, a motor operatively connected thereto, a pole changer associated with said motor, a plurality of electro-magnetic circuit closers, operative in one direction only, disposed along the tracks and connected with opposite terminals of the pole changer, a second plurality of electro-magnetic circuit closers, operative in one direction only, disposed along the tracks and connected to opposite terminals of the pole changer, the two pluralities of circuit closers being arranged in reverse directions, a series of circuit interrupters, operative in one direction only, disposed along the tracks and adapted to interrupt the circuits of the circuit closers aforesaid, an electro-magnetic switch arranged adjacent to the crossing and adapted for manual closing, and an individual circuit embracing said switch and the opposite terminals of the pole changer, substantially as set-forth.

7. In an electrically actuated gate for railway crossings, the combination of a movable gate arm, a motor operatively connected thereto, a pole changer associated with said motor and comprising a fixed member and a semi-rotary member operatively connected with the gate arm, and a plurality of electro-magnetic circuit closers, operative in one direction only, disposed along the tracks in reversed relation for actuation by trains moving in opposite directions respectively and connected with opposite terminals of the fixed member of the pole changer, substantially as set-forth.

8. In an electrically actuated gate for railway crossings, the combination of a movable gate arm, a motor operatively connected thereto, a pole changer associated with said motor and comprising a fixed member and a semi-rotary member operatively connected with the gate arm, a plurality of electro-magnetic circuit closers, operative in one direction only, disposed along the tracks and connected with opposite terminals of the fixed member of the pole changer, and a circuit interrupter, operative in one direction only, disposed along the tracks and adapted to interrupt the circuit of one of the circuit closers aforesaid, substantially as set-forth.

9. In an electrically actuated gate for railway crossings, the combination of a movable

- gate arm, a motor operatively connected thereto, a pole changer associated with said motor and comprising a fixed member and a semi-rotary member operatively connected 5 with the gate arm, a plurality of electro-magnetic circuit closers, operative in one direction only, disposed along the tracks and connected with opposite terminals of the fixed member of the pole changer, a second 10 plurality of electro-magnetic circuit closers, operative in one direction only, disposed along the tracks and connected with opposite terminals of the fixed member of the pole changer, the two pluralities of circuit 15 closers being arranged in reverse directions, and a series of circuit interrupters, operative in one direction only, disposed along the tracks and adapted to interrupt the circuits of the circuit closers aforesaid, substantially 20 as set-forth.
10. In an electrically actuated gate for railway crossings, the combination of a movable gate arm, a motor operatively connected thereto, a pole changer associated with said motor, and a plurality of electro-magnetic circuit closers, operative in one direction only, disposed along the tracks in reversed relation for actuation by trains moving in opposite directions respectively 25 and connected with opposite terminals of the pole changer, each circuit closer comprising in part a floating operating bar operatively connected to a contact member adapted to close the circuit of the mechanism, substantially 30 as set-forth.
11. In an electrically actuated gate for railway crossings, the combination of a movable gate arm, a motor operatively connected thereto, a pole changer associated with said motor, a plurality of electro-magnetic circuit closers, operative in one direction only, disposed along the tracks and connected with opposite terminals of the pole changer, and a circuit interrupter, operative 35 in one direction only, disposed along the tracks and adapted to interrupt the circuit of one of the circuit closers aforesaid, each circuit interrupter having a floating operating bar carrying a contact member adapted to open the circuit of the mechanism, substantially 40 as set-forth.
12. In an electrically actuated gate for railway crossings, the combination of a movable gate arm, a motor operatively connected thereto, a pole changer associated with said motor, a plurality of electro-magnetic circuit closers, operative in one direction only, disposed along the tracks and connected with opposite terminals of the pole 45 changer, a second plurality of electro-magnetic circuit closers, operative in one direction only, disposed along the tracks and connected to opposite terminals of the pole changer, the two pluralities of circuit closers being arranged in reverse direction, and a series of circuit interrupters, operative in one direction only, disposed along the tracks and adapted to interrupt the circuits of the circuit closers aforesaid, each circuit interrupter having a floating operating bar carrying a contact member adapted to open the circuit of the mechanism, substantially 50 as set-forth.
13. In an electrically actuated gate for railway crossings, the combination of a movable gate arm, a motor operatively connected thereto, a pole changer associated with said motor, a plurality of electro-magnetic circuit closers, operative in one direction only, disposed along the tracks and connected with opposite terminals of the pole changer, and a circuit interrupter, operative in one direction only, disposed along the tracks and adapted to interrupt the circuit of one of the circuit closers aforesaid, each circuit interrupter having a floating operating bar carrying a contact member adapted to open the circuit of the mechanism, substantially 55 as set-forth.
14. In an electrically actuated gate for railway crossings, the combination of a movable gate arm, a motor operatively connected thereto, a pole changer associated with said motor, a plurality of electro-magnetic circuit closers, operative in one direction only, disposed along the tracks and connected with opposite terminals of the pole changer, a second plurality of electro-magnetic circuit closers, operative in one direction only, disposed along the tracks and connected to opposite terminals of the pole changer, the two pluralities of circuit closers being arranged in reverse direction, and a series of circuit interrupters, operative in one direction only, disposed along the tracks and adapted to interrupt the circuits of the circuit closers aforesaid, each circuit interrupter having a floating operating bar carrying a contact member adapted to open the circuit of the mechanism, substantially 60 as set-forth.
15. In an electrically actuated gate for railway crossings, the combination of a movable gate arm, a motor operatively connected thereto, a pole changer associated with said motor, and a plurality of electro-magnetic circuit closers, operative in one direction only, disposed along the tracks and connected with opposite terminals of the pole changer, each circuit closer having a floating operating bar, U-shaped in cross-section, operatively connected to a contact member adapted to close the circuit of the mechanism, substantially 65 as set-forth.
16. In an electrically actuated gate for railway crossings, the combination of a movable gate arm, a motor operatively connected thereto, a pole changer associated with said 70

- motor, a plurality of electro-magnetic circuit closers, operative in one direction only, disposed along the tracks and connected with opposite terminals of the pole changer, 5 and a circuit interrupter, operative in one direction only, disposed along the tracks and adapted to interrupt the circuit of one of the circuit closers aforesaid; each circuit closer having a floating operating bar, U-shaped in cross-section, operatively connected to a contact member adapted to close the circuit of the mechanism, substantially as set-forth.
17. In an electrically actuated gate for railway crossings, the combination of a movable gate arm, a motor operatively connected thereto, a pole changer associated with said motor, a plurality of electro-magnetic circuit closers, operative in one direction only, disposed along the tracks and connected with opposite terminals of the pole changer, 15 a second plurality of electro-magnetic circuit closers, operative in one direction only, disposed along the tracks and connected to opposite terminals of the pole changer, the two pluralities of circuit closers being arranged in reverse directions, and a series of circuit interrupters, operative in one direction only, disposed along the tracks 20 and adapted to interrupt the circuit of the circuit closers aforesaid, each circuit closer having a floating operating bar, U-shaped in cross-section, operatively connected to a contact member adapted to close the circuit 25 of the mechanism, substantially as set-forth.
18. In an electrically actuated gate for railway crossings, the combination of a movable gate arm, a motor operatively connected thereto, a pole changer associated with said 30

- motor, a plurality of electro-magnetic circuit closers, operative in one direction only, disposed along the tracks and connected with opposite terminals of the pole changer, and a circuit interrupter, operative in one direction only, disposed along the tracks and adapted to interrupt the circuit of one of the circuit closers aforesaid, each circuit interrupter having a floating operating bar, U-shaped in cross-section, carrying a contact member adapted to open the circuit of the mechanism, substantially as set-forth.
19. In an electrically actuated gate for railway crossings, the combination of a movable gate arm, a motor operatively connected thereto, a pole changer associated with said motor, a plurality of electro-magnetic circuit closers, operative in one direction only, disposed along the tracks and connected with opposite terminals of the pole changer, a second plurality of electro-magnetic circuit closers, operative in one direction only, disposed along the tracks and connected to opposite terminals of the pole changer, the two pluralities of circuit closers being arranged in reverse directions, and a series of circuit interrupters, operative in one direction only, disposed along the tracks and adapted to interrupt the circuit of the circuit closers aforesaid, each circuit interrupter having a floating operating bar, U-shaped in cross-section, carrying a contact member adapted to open the circuit of the mechanism, substantially as set forth.

Signed at Chicago, Illinois, this 5th day of January, A. D. 1916.

ISIDORO BETTINARDI.
ADOLFO TALPO.

Copies of this patent may be obtained for five cents each, by addressing the "Commissioner of Patents, Washington, D. C."
